UNITED STATES PATENT OFFICE

ROBERT E. PIERCE, OF ST. LOUIS, MISSOURI, ASSIGNOR TO BEMIS BRO. BAG CO., OF ST. LOUIS, MISSOURI, A CORPORATION OF MISSOURI

THREAD PULL UP FOR SEWING MACHINES

Application filed October 7, 1925. Serial No. 61,024.

My invention relates to improvements in thread pull-ups for sewing machines, and has for its primary object a thread pull-up which operates with the descent of the needle-bar in such manner that a retrograde movement of the needle thread through the eye of the needle is caused during the last portion of the descent of the needle, whereby a previously formed stitch is drawn up and tightly seated against the under side of the fabric.

A further object is to construct a needle thread pull-up for sewing machines, which is adjustable so that the amount of pull-up and the time at which it commences can be regulated to suit various requirements of work.

In the drawings:

Fig. 1 is a front view of a sewing machine 20 with my device applied thereto;

Fig. 2 is a top plan view of the same;

Fig. 3 is an enlarged section taken on the line 3—3 of Fig. 1;

Fig. 4 is a top plan view of the collar 25 mounted on the needle bar which carries the thread tension;

Fig. 5 is a side view of the same, looking in the direction of the arrow 5;

Fig. 6 is a similar view, looking in the direction of the arrow 6;

Fig. 7 is a vertical sectional view of the collar employed;

Fig. 8 is a side elevation of the same;

Fig. 9 is a top plan view of the stud employed in the thread tension;

Fig. 10 is a side view, looking in the direction of the arrow 10;

Fig. 11 is a view of the spring employed;

Fig. 12 is a face view of the arm forming part of the pull-up;

Fig. 13 is a side elevation of the same;

Fig. 14 is a view of the stud mounted in the head which co-acts with the thread tension on the needle bar;

Fig. 15 is a horizontal section showing the manner of securing the arm therein;

Fig. 16 is a perspective view of the arm which is mounted in the stud illustrated in Figs. 14 and 15, and

Fig. 17 is a diagrammatic view repre-

senting the relative movement of the needle eye, the various pull-up devices, and the movement of the thread during movement of the needle.

In carrying out my invention I employ a 55 machine comprising a base 17 which has an integral arm 18. This arm is provided with a head 19, which is provided with suitable bearings 20 in which the needle bar 21 is mounted. The lower end of the needle bar 60 is tapered and screw-threaded, and slotted as at 22, to receive the nut 23. This nut is also provided with a tapered bore so that when the same is screwed up on the tapered portion 22 the needle 24 will be tightly grasped. 65

Extending through the arm 18 is a shaft 25, which is provided with a sheave wheel 26, so that it can be placed in rotation by means of a belt.

Mounted on the shaft 25 is an eccentric 27, 70 which is surrounded by an eccentric strap 28. Projecting from the eccentric strap is a rod 29, which in turn has secured to its upper end a bearing 30 in which a ball formed integral with the needle bar lever 31 is located. The 75 needle bar lever 31 is pivoted to the arm 18 at the point indicated by the numeral 32. The free end 33 of the needle bar lever is provided with links 34, which are pivotally secured at one end thereto, their opposite ends being secured to a sleeve 35 mounted on the needle bar so that upon rotation of the wheel 26 the needle bar lever 31 will oscillate about the pivot 32 and cause the needle bar 21 to reciprocate vertically. 80

Mounted on the arm 18 is a housing 36 which carries an intermittently applied tension 37. This intermittent tension is operated by means of an arm 38, which arm in turn is moved up and down by means of the stud 39 carried by the needle bar lever 31. 40 represents the ordinary pan or constant tension common to any sewing machine. 85

The arm 38 is provided with screw threads which work on a screw-threaded stud 41 carried by the housing 36 so that upon depression of the needle bar lever 31 the arm 38 will be rocked and ride backward and forward on the stud 41 causing the pan 42 to be forced toward the pan 43 and thus clamp the 100

thread between the pans and hold it against ready movement.

Secured to the needle bar lever 31 is a loop 44, the purpose of which will be explained in detail later. Carried by the arm 18 is an arm having a slotted portion 45 and a rounded portion 46. This rounded portion extends at right angles to the portion 45 and is rounded so that there will be no sharp edges contacting with the thread. This arm is adjustably secured to the arm 18 by means of a screw 47.

The head 19 is provided in its upper surface with a circular opening in which is forced a split stud 48. This stud has openings 49 and 50 formed therethrough and at right angles to each other. One portion of the opening 50 is screw-threaded to receive the screw 51 by means of which the rod or arm 52 is held in adjusted position adjacent the needle bar.

Surrounding the upper portion of the needle bar is a collar 53 which is provided with a screw-threaded boss 54 in which is located a screw 55 for the purpose of securing the collar to the needle bar. The collar is also provided with a boss 56, which is provided with a bore 57 in which the stud 58 has its portion 59 inserted. The boss 56 is also provided with a screw threaded opening at right angles to the bore 57 for the reception of a screw 60 which secures the stud in position, the end of the screw 60 contacting with the flat portion 61 of the reduced portion 59, thus securely holding the stud.

The stud has extending therethrough a cylindrical opening 63 and cut into this opening is a passage-way 64 which leads from one side of the stud and permits the insertion of the needle thread without the trouble of threading it through the opening.

Surrounding the stud 58 is a sleeve 65, which is provided with a head 66. This head is provided with a tapered face 67 (see Figs. 7 and 8) which is for preventing sharp edges from contacting with the thread.

The stud 58 is also provided with a head 68, between which and the head 66 of the sleeve 65 the coil spring 69 is interposed. In this manner I obtain a slight constant tension on the needle thread sufficient to prevent a double loop from forming when the machine is in operation and by this means also the needle thread is retained in the bore 63. The machine is also provided with a bar 70 which has an opening 71 formed therein, through which the thread is first passed, and which serves to guide it to the pan tension 40.

I have not shown the mechanism which operates the under thread, as this forms no essential part of my device, because I may use either the looper or a shuttle in conjunction with my thread pull-up and achieve the same results. It is to be understood, however, that my device is to be operated in conjunc-

tion with a sewing machine employing two threads.

In threading my device, the thread is first passed through the opening 71 formed in the bar 70, then between the pan or constant tension 40, then between the intermittent tension. It is then threaded through the loop 44, then brought down through the opening 63 in the stud 58 and finally through the eye of the needle.

The material to be sewed is placed under the presser-foot and the machine started in the usual manner. Upon the descent of the needle, the needle will first penetrate the goods and the concatenation of the threads will take place. Upon further descent of the needle and the downward movement of the needle bar and needle bar lever, the intermittent lock will be operated, clamping the thread between the pans 42 and 43 and preventing any further thread being drawn from the source of supply. This locking takes place before the needle has reached its lowest point of descent.

A further downward movement of the needle bar and its operating lever will cause the stud 58 and the eye 44 to pass below the top of the arms 52 and 46. By so doing it will be necessary to supply additional thread which, since the source of supply is locked, can only be obtained from the previously formed stitch, and then only by pulling up on that branch of needle thread between the intermittent tension and the needle. This pulling-up movement causes a retrograde movement of the needle thread through the eye of the needle, thus tightly drawing up the previously formed stitch. In other words, the loop of needle thread which surrounds the thread supplied either by the looper or the shuttle is tightly drawn. The adjustment is made by loosening the screw 47 and sliding the arm 45 up and down or rocking it to or from the head 19. The stud 48 may also be raised or lowered if found necessary, so as to get more or less pull on the needle thread. However, for ordinary adjustments I have found that the screw 47 answers all purposes.

While I have shown and described a particular kind of thread lock, I do not desire to limit myself thereto, the only essential feature being that the thread lock be placed adjacent the pan or constant tension or the source of supply, so that when the pull-up occurs the thread will be locked between the point of pull-up and the source of supply, and therefore a retrograde movement of the needle thread through the eye of the needle occurs during a portion of the needle's descent.

Having fully described my invention, what I claim is:

1. A device of the class described comprising a sewing machine having an arm, a head integrally carried thereby, a needle bar mounted in said head, a needle bar lever

mounted on said arm for operating said needle bar, a needle carried by said bar, a slotted adjustable arm mounted on the sewing machine arm, an adjustable arm carried by the head, means carried by the needle bar lever and the needle bar and co-acting with the arms carried by the head and the sewing machine arm for imparting a pull-up on the needle thread during the last portion of the needle descent, and means carried by the sewing machine arm for clamping and arresting the feed of needle thread from a source of supply while the pull-up is applied.

2. In a sewing machine having an arm, a head, a needle bar, a needle, a needle bar operating lever, and an intermittent thread lock for arresting the feed of needle thread from and adjacent a source of supply, an adjustable slotted arm located on said arm, an adjustable bar carried by said head and co-acting with means located on the needle bar and needle bar operating lever whereby a pulling up movement of the needle thread between the needle and the intermittent thread lock is produced during the descent of the needle and while the thread is locked, and means for adjusting the means on the arm and head whereby the amount of pull-up can be regulated.

3. A device of the class described comprising in combination with a sewing machinehead, an arm integral therewith and the operating mechanism carried thereby, a constant tension, and means carried by the arm and adjacent the constant tension for intermittently arresting the feed of needle thread during a portion of the needle descent, a pivoted lever carried by the arm of said machine for operating a needle bar, a slotted adjustable arm carried by the arm of said machine above the pivoted lever and extending beyond said lever, an arm carried by the head of the machine, means carried by the needle bar and by its operating lever and co-acting with the slotted adjustable arm carried by the arm of the machine and the arm carried by the head of the machine during a portion of the needle descent for producing a retrograde movement of the needle thread through the eye of the needle while the needle thread feed is arrested.

4. A device of the class described, the combination with a sewing machine having an arm, a head integral with said arm, a needle bar mounted in said head, a needle bar lever pivotally mounted on said arm, and a link for operatively connecting said needle bar and needle bar lever, of a constant thread tension carried by said arm adjacent its rear end, an intermittent tension mounted on the upper face of said arm in advance of the constant tension, an arm pivotally carried by said intermittent tension and adapted to be moved up and down by said needle bar lever for operating said intermittent tension,

a loop carried by the needle bar lever in advance of the intermittent tension, an adjustable slotted L shaped arm carried by the sewing machine arm and adjacent the head, a stud carried by the sewing machine head and projecting upward therefrom, an adjustable arm projecting horizontally from said stud, and a spring-actuated constant tension secured to said needle bar at its upper end.

In testimony whereof I have affixed my signature.

ROBERT E. PIERCE.
